V. O'CONNELL

TOILET ACCESSORY

Filed Aug. 9, 1922

INVENTOR
V. O'Connell

BY

M. O'Connell
ATTORNEY

Patented May 1, 1923.

UNITED STATES PATENT OFFICE.

VINCENT O'CONNELL, OF NEW YORK, N. Y.

TOILET ACCESSORY.

Application filed August 9, 1922. Serial No. 580,648.

To all whom it may concern:

Be it known that I, VINCENT O'CONNELL, a citizen of the United States, residing at New York, in the county of New York and State of New York, have invented certain new and useful Improvements in Toilet Accessories, of which the following is a specification.

This invention relates to improvements in toilet accessories, with particular reference to manicuring requisites, and has as its object to provide a neat compact case suited to be carried in a small pocket or hand bag without inconvenience.

A further object is to hingedly engage, in the ends of the case, a number of the more necessary implements, each being so mounted that the case acts effectively as a handle for the individual implement turned outward for operative purposes.

Another aim is in the provision of a convenient and commodious set of encased tools, each being easily accessible and all prevented from displacement.

The objects are secured by the novel construction and arrangement of parts hereafter described and shown in the accompanying drawing, forming part of this disclosure, and in which:

Figure 1 is a plan view of the toilet case, shown in an open position to disclose its construction and display the articles therein, one being extended as for use.

Figure 2 is a side view of the same as closed.

Figure 3 is an edge view thereof, one implement being extended.

Figure 4 is a view looking at the side of the casing carrying the fastenings.

Figure 5 is an end view of the same.

The device, as shown in the drawing, includes a pair of thin sheet metal casings substantially alike, each consisting of a plate 10 and 11 having raised flanges 12 and 13 around its four sides, the shape being that of an elongated rectangle.

These two casings are joined along one of their longer edges by a hinge 14 and carry on their opposite edges leaf springs 15 secured by rivets 16 near the center of length of each casing.

One of the springs is extended adjacent the inner flange to the right and the other to the left, to points near the end walls, and each spring is provided with cam faced catches 17 engageable, when the case is

closed, in corresponding openings 18 in the mating side.

Also carried by the springs are extensions 19 passing through openings 20 in the same flange and adapted to be pressed inward by finger contact, thus releasing the casing sides when it is desired to open the case.

Obviously when closing the two sides, the catches spring inwardly until they enter the openings provided for them, thus locking the case.

Fixed in the opposite ends of each casing are metal blocks 21 containing pairs of spaced transverse slots 22, these slots being continued completely through adjacent end walls of the casings as at 23, and drilled openings pass at right angles through the blocks to receive hinge pins 24.

Pivoted on these pins, in the slots 22 are the shanks of the various implements, as for instance at one end, a buffer 25 and a knife 26, and at the other end, a file 27 and scissors 28, all of which are so shaped and suited to fold within the walls of the case and allow it to be closed when not in use.

Each implement may be individually extended and when so positioned, the case may be closed, the flanged end opposite the slots, together with the walls of the slots operating to hold the implement firmly and securely while the closed case acts as a handle for the manipulation of the implement extended.

Obviously other implements may be substituted for those shown and mentioned, and the case may be lined with leather or fabric as desired, its exterior being finished to suit the taste.

Having thus described my invention, what I claim as new and desire to secure by Letters Patent, is:

1. A casing comprised of two equal oblong rectangular halves, a hinge connecting said halves along one of their longer edges, releasable snap fastenings on the opposite edges of each half, slotted blocks fixed in the opposite ends of each half casing, the slots extending through the end walls of the casings, and a plurality of various implements hingedly engaged within the mentioned slots of said blocks, said implements being adapted to extend individually outward or fold within the casing.

2. A casing comprised of two equal oblong rectangular halves, a hinge connecting

said halves along one of their longer edges, releasable snap fastenings on the opposite edges of each half, slotted blocks fixed in the opposite ends of each half casing, the 5 slots extending through the end walls of the casings, pins passing transversely through said blocks intersecting the slots therein, shanks pivoted on said pins, said

shanks being arranged in pairs at end of the casing, and a plurality of implements 10 formed with said shanks, said implements when extended being clamped by the other of said half casings.

In witness whereof I have affixed my signature.

VINCENT O'CONNELL.
